UNITED STATES PATENT OFFICE.

HUGO F. SPENGLER, OF CHICAGO, ILLINOIS.

AUTOMATIC STOP FOR PHONOGRAHS.

Application filed July 23, 1920. Serial No. 398,405.

To all whom it may concern:

Be it known that I, HUGO F. SPENGLER, a citizen of the German Republic, and a resident of Chicago, in the county of Cook and State of Illinois, have invented certain new and useful Improvements in Automatic Stops for Phonographs; and I do hereby declare that the following is a full, clear, and exact description thereof, reference being had to the accompanying drawings, and to the letters of reference marked thereon, which form a part of this specification.

This invention relates to improvements in automatic stops for phonographs, and consists of the matters hereinafter described and more particularly pointed out in the appended claims.

The object of the invention is to provide a simple and efficient device which may be set with reference to the last sound groove of a record to be played, so that said device will automatically operate to stop the rotation of the turn table, one or more revolutions after said last sound groove has been played, to insure the full and complete playing of the entire record.

This object of the invention, as well as others, together with the many advantages thereof, will more fully appear as I proceed with my specification.

In the drawings:—

Fig. 1 is a fragmentary top plan view of a phonograph showing my improved automatic stop applied thereto.

Fig. 2 is a side elevation of the parts shown in Fig. 1.

Fig. 3 is a horizontal sectional view, on an enlarged scale, taken on the line 3—3 of Fig. 2.

Fig. 4 is a view similar to Fig. 3 but with some of the parts shown in changed relation.

Fig. 5 is a vertical detail sectional view taken on the line 5—5 of Fig. 3.

Fig. 6 is a vertical detail sectional view taken on the line 6—6 of Fig. 4.

Fig. 7 is a vertical detail sectional view taken on the line 7—7 of Fig. 3.

Fig. 8 is another vertical detail sectional view taken on the line 8—8 of Fig. 3.

Figs. 9, 10, 11, 12, 13 and 14 are detail perspective views of parts of the automatic stop, which will be referred to more particularly as I proceed with my specification.

Referring now in detail to that embodiment of the invention illustrated in the

drawings: 15 indicates the horizontal top platform of a disc record phonograph, 16 indicates the record turn table and 17 indicates the swinging tone arm. The turn table is of the usual kind, having a depending, 60 peripheral annular flange 18 and the tone arm is of the usual kind which carries a reproducer 19 at its free end, said reproducer including a holder 20 for a stylus or pin 21. The construction thus far set forth is general as to any disc record phonograph to which my improved automatic stop is adapted to be applied.

My improved stop is mounted on a rectangular base plate 25, which is adapted to 70 be secured to the platform 15 adjacent the base flange of the tone arm, so as to partially extend beneath and be covered by the turn table.

On said plate, extending longitudinally 75 along one edge thereof, is an endwise movable bar 26, which carries a brake shoe or friction block 27, adapted to be engaged with and disengaged from the inner surface of the peripheral flange 18 of the turn table. 80 Said bar 26 has a longitudinal slot 28 in that end normally beneath the turn table, through which a screw 29 threaded into the base plate 25, extends to guide the bar in its movement. A leaf spring 30 fixed to said 85 plate, normally acts to move said bar outwardly so that the brake shoe 27 will engage the flange of the turn table. On the other or outer end of said bar is an upright pin 31, which engages in a slot 32 in the free, 90 33 (see Fig. 14) which is pivoted to the plate 25 by a screw 34.

An operating lever 35 is pivoted at about its middle to swing in a horizontal plane, on 95 a screw 36 fixed to the base plate 25. The shorter arm 37 of the lever has a thumb screw 38, while the longer arm 39 of said lever projects into the vicinity of the forked end of the lever 33 and has a depending pin 100 40 which engages the forked end of said lever. A leaf spring 41 which is fixed to the shorter arm 37 of the lever 35 and engages at its free end against an upright post 42 arising from the plate 25, normally holds 105 the lever in this position.

Arranged at right angles to and extending across the forked lever 33 is a leaf spring 45 (see Fig. 13) which is fixed to the plate 25 by a screw 46, beneath the turn table 16. 110

The free end of said spring has a longitudinal slot 47 and near the middle of said spring on its under side, is a depending catch pin 48, the bottom surface of which is inclined as shown in Fig. 5. As the lever 33 is moved from the position shown in Fig. 3 to that shown in Fig. 4, its pin 40 will swing the lever 33 about its pivot 34 and at the same time will move the brake bar 26 inwardly against the action of the spring 30, removing the brake shoe 27 from the turn table flange 18. As the lever 33 thus swings, its inner edge which is beveled, engages the inclined surface of the pin 48 of the spring 45 and elevates the same so that it passes beneath the pin which thereafter engages the outer edge of said lever and holds it together with the bar 26 in the position shown in Fig. 4, wherein the turn table is free to rotate. When the spring 45 is again actuated, as will be hereinafter described, to release the arm 33, the spring 30 will move the bar 26 outwardly, so that the brake shoe 27 will again engage the flange of the turn table and stop the same.

Means are provided to retard the too rapid in and out movement of the brake bar 26 and such means is as follows:

Secured to the base plate 25 near the spring 30 of the bar 26 is a shallow, rectangular casing 50 (see Fig. 3). On a vertical pin 51 in said casing is pivoted a segmental gear 52 which has an arm 53, the outer end of which is connected as at 54 to the bar 26 at a point between the brake shoe 27 and the slot 28. The segmental gear 52 meshes with a pinion 55 made integral with a larger gear 56 on an upright pin 57 spaced from the pin 51. The gear 56 meshes with two pinions 58 on pins 59, said pinions carrying radial fan blades 60. Thus while the bar 26 is moving inwardly or outwardly, it will rotate the gearing in the casing which by reason of the resistance thereof, together with the resistance of the fan blades, will act to retard or govern the movement of the bar 26 when the lever 33 is released. While I have illustrated and described this particular form of governor, I wish it to be understood that I am not limiting myself thereto, as I may as readily employ any other means which will retard the movement of the bar 26.

Arising from the base plate 25 at a point between the pivot screws 34-36 is an upright standard 62, which includes an arcuate extension 63 struck about the vertical axis of the tone arm as a center (see Figs. 2, 3 and 7). The extension 63 overhangs a part of the lever 33 and the forked end of the associated spring arm 45. Fixed to the top surface of said standard and extension is an arcuate block 65 (see Fig. 7 and Fig. 9) which has a horizontal slot 66 in that end above the standard 62 and a vertical groove 67 in its inner surface near its other end.

The block is of a radial width less than that of the standard and its extension so that an outwardly extending radial flange 68 (see Fig. 5) is provided at the bottom outer surface of said block.

Frictionally engaged against the outer surface of the block 65 is an arcuate edge-wise arranged plate 70, which rests at its bottom edge upon the flange 68. Said plate has a notch 71 in its top edge near one end and has a longitudinal slot 72 which opens through its other end. A leaf spring 73 fixed in the slot 66 of the block 65 by screws 74 and engaging with the bottom wall of the slot 72 in the plate 70 holds said plate 80 against the flange 68, while a coiled spring 75 on a thumb screw 76 which extends through the slot 72 in the plate 70 and is threaded into the block 65, acts to frictionally hold said plate in position with respect to the block 65.

In the vertical groove 67 of the block 65 is slidably arranged a T-shaped member 80 (see Fig. 10) which includes an upright slotted body part 81, a top arcuate cross head 82 and a bottom cam foot or extension 83, arranged at right angles to the cross head. A screw 84 (see Fig. 5) extending through the slot in the body and threaded into the block 65, holds said member 80 in place in the groove 67 so that it may move vertically therein. The cam foot or extension 83 is beveled outwardly and upwardly toward its free end which overhangs a part of the long arm 39 of the operating lever.

On the upright part of the tone arm in line with, but below the horizontal part thereof, is a horizontal bracket arm 90 which has a longitudinal groove 91 opening through its bottom surface (see Fig. 5). In said groove is a pawl or detent 92 which swings vertically about its inner pivoted end 93. A leaf spring 94 fixed in said groove acts to swing said pawl downwardly, a cross pin 95 in the arm limiting this downward movement. In the bottom edge of the pawl near its free end is provided a notch 96 which registers with the cross head 82 of the T member 80. The bracket arm 90 is made long enough to overhang the arcuate plate 70 so that in the operation of the tone arm as it moves under the action of the sound groove, the bottom surface of the said pawl will have sliding engagement on the top edge of the arcuate plate 70.

On the outer surface of the upright post 42, before mentioned, arising from the plate 25, is mounted so as to move in a vertical plane, a trip plate 98 (see Figs. 5 and 11). This plate is preferably arranged in the plane of a radial line extending between the axis of the tone arm and the T member 80 before mentioned. The upright part 99 of said trip plate has a vertical slot through which screws 100 on the standard 42 extend,

so that the trip plate is capable of a vertical sliding, guided movement on said standard. At the top end of said upright part 99 is a horizontal extension or platform 101, by means of which said trip plate is actuated.

The bottom end of said upright part 99 normally rests upon one end of a rocking block 102 (see Figs. 6 and 12), the other end of which extends beneath the slotted end of the spring arm 45. An upright pin 103 on said last mentioned end of the rocker engages within the slot 47 of said spring arm. Between its end said rocker has a tapered hole 104 in which is engaged a pin 105, rising from the base plate 25. Said pin and hole are so related that the rocker is capable of a limited vertical rocking movement on the plate 25 but is held against a horizontal swinging movement by reason of its pin connection with the spring arm 45. Thus when pressure is exerted upon the platform 101 of the trip plate 98, its bottom end will depress the associated end of the rocker and lift the other end which in turn will lift the slotted end of the spring arm 45 and thus release the lever 33 from its locked position shown in Fig. 4.

The operation of the stop is as follows:

Assume that the parts are in the position shown in Figs. 1 and 3 wherein the brake shoe 27 has engaged the flange 18 of the turn table 16 and stopped its rotation, and the latch 92 is engaged in the notch 71 in the arcuate plate 70. The record just played is removed in the usual manner and another record is placed upon the turn table. The tone arm is moved inwardly to bring the stylus 21 into register with the last active sound groove of the record. In this movement of the tone arm to set the stop as a whole with reference to the last sound groove, the frictionally held, arcuate plate 70 moves about the arcuate block 65, with the tone arm because of the engagement of the latch 92 within the notch 71 in said plate 70. Thus is this notch brought into its proper position with reference to the last sound groove of the record now to be played. As the last sound grooves of different records vary in diameter, the device may be readily set in this manner to meet the requirements of each individual record to be played.

The knob 38 of the lever 35 is next swung toward the base of the tone arm 17 by thumb pressure. This will swing its other end in the opposite direction, when by reason of the pin 40, a swinging movement will be imparted to the lever 33 and simultaneously an endwise movement is imparted to the brake bar 26 so that the brake shoe 27 is moved away from the turn table flange 18 to release the same which now starts its rotation. As the lever swings to the left, as shown in the drawings, it will engage the

inclined surfaced pin 48 on the spring arm 45 and lift the same to pass beneath, when said pin will engage the other side of the lever and lock it in this position. As the bar 26 moves, it will actuate the governor mechanism in the casing 50 in one direction.

The operating lever 35, when operated, will at the same time strike the inclined surface of the toe 83 on the member 80 and lift the same vertically. The cross head 82 of said member being in engagement with the pawl 92, will lift the same to release it from the notch 71 in the plate 70. With the tone arm pawl thus released, said tone arm may now be swung about its vertical axis to bring the stylus into position to engage the starting groove of the record. The stylus is then inserted into the starting sound groove and the playing commences.

As the tone arm swings toward the last sound groove of the record, under the action of the stylus following the sound grooves, the pawl 92 will slide along the top edge of the arcuate plate 70 until it registers with the notch 71 in said plate, which registration takes place when the stylus has reached the last sound groove of the record. When the pawl thus registers with the notch 71, the spring 94 will swing the pawl 92 downwardly into the notch. Simultaneously therewith, said pawl will strike the platform 101 of the member 98 and depress the same so as to tilt the rocker 102. This will elevate the forked end of the spring arm 45 to lift the pin 48 out of locking engagement with the lever 33, to release the same. When this lever is thus released, the leaf spring 30 will move the brake bar 26 outwardly. This outward movement is slowed down or retarded under the action of the governor mechanism in the casing 50, so that a period of time elapses between the time when said stylus reaches the last sound groove and the brake shoe engages the turn table flange, which period of time permits of one or more rotations of the turn table to insure a full and complete playing of the record.

When another record is to be played, the stylus is set with reference to the last sound groove of that record as before described.

The advantage of the invention is apparent. A full and complete playing of the record is provided for by permitting one or more rotations of the turn table after the stylus reaches the last sound groove.

The device may be attached to any disc record phonograph and is positive and automatic in its operation.

While in describing my invention, I have referred to certain details of mechanical construction and arrangement of parts. I do not wish to be limited thereto, except as may be pointed out in the appended claims.

I claim as my invention:

1. A device of the kind described, com-

- prising in combination with the turn table and the tone arm of a phonograph, a brake shoe normally acting to engage the turn table, means for holding said brake shoe away from the turn table and operable when the stylus of the tone arm engages the last sound groove of the record being played to release said brake shoe, and means retarding the movement of the brake shoe toward the turn table to permit one or more rotations thereof before said brake shoe engages and stops said turn table.
2. A device of the kind described, comprising in combination with the turn table and the tone arm of a phonograph, a brake shoe normally acting to engage the turn table, means for holding said brake shoe away from the turn table, means for releasing the brake shoe holding means when the stylus of the tone arm reaches the last sound groove of the record being played, said means being capable of adjustment to meet the variation of diameters of the last sound groove of different records, and means retarding the movement of the brake shoe toward the turn table to permit one or more rotations thereof before said brake shoe engages and stops said turn table.
3. A device of the kind described comprising in combination with the turn table and the tone arm of a phonograph, a brake shoe adapted to engage the turn table, a manually operable lever for moving said brake shoe out of engagement with said turn table, a catch for locking the brake shoe in this position, a trip member actuated when the stylus reaches the last sound groove of the record being played, for releasing said brake shoe locking catch, and means retarding the movement of the brake shoe toward the turn table when released to permit one or more further rotations of the turn table before said brake shoe engages and stops said turn table.
4. A device of the kind described comprising in combination with the turn table and the tone arm of a phonograph, a brake shoe adapted to engage the turn table, a manually operable lever for moving said brake shoe out of engagement with said turn table, a catch for locking the brake shoe in this position, a trip member actuated when the stylus reaches the last sound groove of the record being played for releasing said brake shoe locking catch, a plate controlling the operation of said trip member, adjustable with reference to the last sound groove of the record to be played, and means retarding the movement of the brake shoe toward the turn table when released, to permit one or more rotations of the turn table before said brake shoe engages and stops said turn table.
5. A device of the kind described, comprising in combination with the turn table and the tone arm of a phonograph, a brake shoe adapted to engage the turn table, a manually operable lever for moving said brake shoe out of engagement with said turn table, a catch for locking the brake shoe in this position, a trip member actuated when the stylus reaches the last sound groove of the record being played for releasing said brake shoe locking catch, a plate controlling the operation of said trip member, a pawl carried by the tone arm and operating in the setting of the stylus with reference to the last sound groove of the record to be played, to set said plate so that said pawl will actuate the trip to release the brake shoe when said stylus reaches said last sound groove, and a governor for retarding the movement of the brake shoe toward the turn table when released, to permit one or more rotations of the turn table before said brake shoe engages and stops said turn table.
6. A device of the kind described, comprising in combination with the turn table and the tone arm of a phonograph, a brake shoe bar, a spring normally acting to engage the brake shoe with the turn table, a lever for moving said brake shoe bar against the action of said spring to disengage the brake shoe from the turn table, a catch member for holding said brake bar in the last mentioned position, a trip plate for releasing the catch, a pawl carried by the tone arm for actuating the trip member to release the catch, when the last sound groove of the record has been reached, and a mechanism connected to the brake bar to retard the movement of the same, to permit one or more rotations of the turn table before the brake shoe engages and stops the rotation of said turn table.
7. A device of the kind described, comprising in combination with the turn table and the tone arm of a phonograph, a brake shoe bar, a spring normally acting to engage the brake shoe with the turn table, a lever for moving said brake shoe bar against the action of said spring to disengage the brake shoe from the turn table, a catch member for holding said brake bar in the last mentioned position, a trip member for releasing the catch, a pawl carried by the tone arm for actuating the trip member to release the catch when the last sound groove of the record has been reached, a plate upon which said pawl engages as the tone arm swings inwardly in following the sound groove of the record, said plate having a notch therein to permit the pawl to actuate the trip plate, and a mechanism connected to the brake bar to retard the movement of the same towards the turn table to permit one or more rotations of the same before the brake shoe engages and stops said turn table.

8. A device of the kind described, comprising in combination with the turn table and tone arm of a phonograph, a brake shoe bar, a spring normally acting to engage the brake shoe with the turn table, a lever for moving said brake shoe bar against the action of said spring to disengage the brake shoe from the turn table, a catch member for holding said brake bar in the last 5 mentioned position, a trip member for releasing the catch, a pawl carried by the tone arm for actuating the trip member to release the catch when the last sound groove of the record has been reached, a 10 plate upon which said pawl engages as the tone arm swings inwardly in following the sound groove of the record, said plate 15
- having a notch therein to permit the pawl to actuate the trip plate, a mechanism connected to the brake bar to retard the movement of the same towards the turn table to permit one or more rotations of the same before the brake shoe engages and stops the turn table, and means operable in the movement of the lever to lift said pawl out of 20 said notch.
- In testimony that I claim the foregoing as my invention, I affix my signature in the presence of two witnesses, this 20th day of July A. D. 1920.
- HUGO F. SPENGLER.
